UNITED STATES PATENT OFFICE.

LEWIS A. WEYBURN, OF ROCKFORD, ILLINOIS, ASSIGNOR TO THE L. A. WEYBURN COMPANY, OF SAME PLACE.

HARROW.

SPECIFICATION forming part of Letters Patent No. 352,383, dated November 9, 1886.

Application filed July 3, 1886. Serial No. 207,097. (No model.)

To all whom it may concern:

Be it known that I, LEWIS A. WEYBURN, a citizen of the United States, residing in the city of Rockford, in the county of Winnebago 5 and State of Illinois, have invented a new and useful Improvement in Harrows, of which the following is a specification.

This invention relates to the teeth employed in harrows. Its object is to divide and pulverize the soil.

It consists in the construction represented in the accompanying drawings, to be herein-after described, and in which—

Figure 1 is an isometrical representation of 15 a tooth embodying my invention, and Fig. 2 is a transverse section on dotted line *a* on Fig. 1.

The harrow-tooth represented in the accompanying drawings is provided with a shank, 1, to engage a beam of the harrow to fix it in place. This shank 1 in this instance is of 20 taper form and cylindrical in transverse section, and its end portion is screw-threaded and provided with a screw-nut, 2, to clamp and hold it in place in the beam. The tooth 3 de- 25 pends from its cylindrical shank portion, and is curved rearward substantially in the segment of a circle, and its extreme rear end portion, 4, is twisted to nearly a horizontal position and is curved downward. The vertical 30 and rearward-curving portion 3 of the tooth, between its shank and its rear end twisted portions, is produced in knife-edge form on its forward convex edge, 5, as shown in section in Fig. 2.

My improved harrow-tooth is designed for 35 use in harrows of the usual construction, and instead of the taper cylindrical shank 1 employed to connect it to the beam, any other known form of attachment capable of use in 40 connection with my improved tooth may be employed.

The use of my improved tooth: In the forward movement of the harrow the knife-edge of the tooth will readily divide the earth, and its twisted rear end will lift and pulverize the 45 ground.

I am aware that previous to my invention it has been proposed to provide a harrow-tooth one end of which was a threaded shank, to secure said tooth to a beam, the remaining portion of the tooth curving downward and rearwardly, at which end the upper and lower corners were bent laterally to a slight extent to form a deflecting portion. I am also aware that it has been proposed to provide a harrow-tooth 55 having its front portion bent horizontally to furnish a fastening portion, the remainder of said tooth depending rearwardly, and having its extremity bent or twisted laterally to a slight extent. In the first construction the 60 ends of the tooth deflect the earth to one side, and in the other case the twisted portion lies below the effective portion of the cutting-edge. In my improved construction the curved cutting-edge approximates a semicircle, so that 65 the rear twisted portion lies in a higher plane, thus insuring the cutting portion entering deep in the ground without interfering with the proper operation of the rear twisted portion.

I claim as my invention—

The herein-described harrow-tooth, consisting of a shank to connect with the harrow-beam, a depending rearward-curving portion produced in convex cutter form and approximating a semicircle, and a rear end twisted 75 to a nearly horizontal position and located in a plane above that of the lower effective portion of the cutter, substantially as set forth.

LEWIS A. WEYBURN.
